UNITED STATES PATENT OFFICE

167,517

CHILD'S MIRROR AND TOILET ARTICLE SHELF UNIT

John E. Kopko, Cleveland, Ohio

Application August 10, 1951, Serial No. 16,228

Term of patent 14 years

(Cl. D33—3)

To all whom it may concern:

Be it known that I, John E. Kopko, a citizen of the United States, residing at Cleveland, county of Cuyahoga and State of Ohio have invented a new, original, and ornamental Design for Child's Mirror and Toilet Article Shelf Unit, of which the following is a specification, reference being had to the accompanying drawing, forming a part hereof;

The single figure is a perspective view of a child's mirror and toilet article shelf unit showing my new design.

I claim:

The ornamental design for a child's mirror and toilet article shelf unit, substantially as shown.

JOHN E. KOPKO.
